UNITED STATES PATENT OFFICE.

GEORGE W. FITZ, OF BOSTON, MASSACHUSETTS.

MASSAGE APPARATUS.

SPECIFICATION forming part of Letters Patent No. 795,212, dated July 18, 1905.

Application filed February 20, 1905. Serial No. 246,378.

To all whom it may concern:

Be it known that I, GEORGE W. FITZ, of Boston, in the county of Suffolk and State of Massachusetts, have invented certain new and useful Improvements in Massage Apparatus, of which the following is a specification.

This invention has for its object to provide a mechanical massage apparatus the acting tool of which shall have a gyratory or orbital motion and be adapted to either rub the body without percussion or to act percussively and shall also be adapted to be easily and conveniently guided and directed against any desired part of the body under treatment, the operation of the tool being practically noiseless and unattended by unreasonable wear of contacting parts.

The invention consists in the improvements which I will now proceed to describe and claim.

Of the accompanying drawings, forming a part of this specification, Figure 1 represents a side elevation, partly in section, of a massage apparatus embodying my invention. Fig. 2 represents a sectional view, on a larger scale, of a portion of the apparatus. Fig. 3 represents a section on line 3-3 of Fig. 2. Fig. 4 represents a side elevation showing the preferred means for flexibly supporting the apparatus.

The same reference characters indicate the same parts in all the figures.

In the drawings, *a* represents a casing in which is journaled a shaft *b*, which may be rotated by any suitable means, such as an electric motor, located in the casing.

c represents a fulcrum-ring supported by an arm or extension *a'*, forming a part of the casing, said ring being adjacent to one end of the shaft and preferably mounted adjustably on the arm *a'* in such manner that it may be moved toward and from said end of the shaft, means being provided, such as a screw-stem *c'*, affixed to an annular ring-holder *c''*, and a clamping-nut *c'''*, engaged with the stem, for securing the ring-holder and ring to the arm in any position to which the ring may be adjusted. The arm *a'* is preferably tubular and is provided with a slot *a''*, in which the stem *c'* is movable. The ring *c* preferably has a relatively thin inner edge bearing on the shank

of the operating-tool. Beside the ring and in contact therewith is a collar *c'*, of felt or other absorbent material, which is saturated with oil and lubricates the contacting surfaces of the ring and shank. The collar *c'* is held in the annular holder *c''*.

d represents the head or acting portion, and *d'* represents the shank of the operating-tool. One end of the shank is engaged eccentrically by the antifrictional means hereinafter described with the shaft *b*, and its opposite end carries the head *d*. The shank passes through the fulcrum-ring *c*, as shown in Fig. 2. The rotation of the shaft causes the shank *d'* to oscillate on its fulcrum, the end portions of the shank and the head *d* being revolved or gyrated in an orbit the diameter of which is determined by the adjustment of the fulcrum-ring. The head *d* therefore has an orbital rubbing motion when the plane of its orbit is approximately parallel with the surface under treatment. This rubbing action is similar to the action of the hand of a masseur and has a more desirable effect in some respects than a percussive action. When, however, the plane of the orbit is substantially or approximately at a right angle with the surface under treatment, the action of the tool will be to a certain extent percussive, although the jar and vibration of the machine are less than would be the case if the tool were reciprocated. Hence the use of the apparatus is less fatiguing to the operator. The shaft *b* is provided with an eccentric antifriction-socket which includes an inner annular ball-race *b'* and an outer annular ball-race *b''*, opposed to the inner race, said races being inserted in an enlargement *b'''*, affixed to the shaft *b*. The inner end of the shank *d'* has a substantially spherical enlargement *d''*, which is interposed between the ball-races *b'* *b''*. Between the said races and the adjacent portions of the enlargement *d''* are interposed balls *b''* *b'''*, which confine the enlargement against displacement in any direction and at the same time permit it to turn freely about its own center in any direction without noise or rattle, the wear of the fixed and moving contacting parts being reduced to the minimum.

The casing *a* is flexibly supported, so that the tool can be directed against any desired part of the body. As here shown, the casing has a pivoted bail *g*, which is attached to one end of a flexible cord or strap *h*, which passes over a pulley or pulleys *i* and is provided with a counterbalancing-weight *j*. The pulleys *i* are mounted on a hanger *k*, having a trolley-wheel *k'*, adapted to run on a track *m*. Said track forms a part of a bracket or crane which is pivoted to fixed bearings *m' m'* in such manner that it can swing in a horizontal plane. The casing is adapted to be turned on the bail sufficiently to give the arm *a'* a vertical direction or a horizontal direction or any other direction. The arm *a'* is adapted to serve as a handle to be grasped by the operator. The casing may be provided with one or more additional handles *q*. One of said handles may be utilized as a support for a switch *p*, adapted to close and break the circuit through the motor.

It will be seen that the head of the operating-tool is practically unobstructed, so that it can be directed either against a surface which is substantially or approximately parallel with the plane of its orbit to cause a rubbing action or against a surface which is at an angle with said plane to cause a percussive action.

o represents an arm adapted to be detachably secured to the shank *d'* and to engage a slotted or forked guide *o'*, affixed to the casing, said arm and guide preventing the rotation of the shank on its own axis. This is particularly desirable when the operating-tool is an applicator adapted for internal use and of irregular shape, so that its rotation would be injurious. The arm *o* is preferably divided at its inner portion by a slot *o''* into two spring-arms *o''*, adapted to bestride the shank *d'* and having flat faces *o'*, bearing on faces *o''*, formed on the shank, the resilience of the arms causing them to firmly engage the shank. The guide *o'* may be affixed by a screw *o''* to the casing *a'*. The arm *o* is removed when the shape of the tool is such that its rotation on its own axis is not objectionable.

50 I claim—

1. A massage apparatus comprising a casing, a shaft journaled therein and provided with an eccentric antifriction-socket, a ful-

crum-ring supported by the casing adjacent to the socket, and a tool-shank fulcrumed in said ring and projecting beyond the end of the casing and having at its inner end an enlargement engaged with said socket and having an operating-head connected with its outer end, the said antifriction-socket engaging both the front and rear of the said enlargement to hold the same against displacement in any direction.

2. A massage apparatus comprising a casing, a shaft journaled therein and provided with two opposed annular ball-races eccentrically arranged, a fulcrum-ring supported by the casing, a tool-shank fulcrumed in said ring and projecting beyond the end of the casing and having an operating-head connected with its outer end, and having at its inner end an enlargement located between said ball-races, and two series of balls interposed between the ball-races and the adjacent surfaces of the enlargement, said balls and races preventing displacement of the enlargement in any direction.

3. A massage apparatus comprising a casing, a shaft journaled therein and provided with an eccentric socket, a fulcrum-ring supported by the casing adjacent to said socket, a tool-shank fulcrumed in said ring and provided at its inner end with an enlargement engaged with said socket, an operating-head connected with the outer end of the shank, the head being gyrated by the rotation of the shaft, an arm detachably affixed to the shank, and a guide for said arm affixed to the casing, said guide and arm preventing rotary movements of the shank and head.

4. A massage apparatus comprising a casing, a shaft journaled in the casing, a fulcrum-ring supported by the casing, an absorbent collar located beside the fulcrum-ring, a shank eccentrically engaged at one end with the shaft and extended through the fulcrum-ring, and a head connected with the opposite end of the shank and gyrated thereby, the contacting portions of the shank and ring being lubricated by the absorbent collar.

In testimony whereof I have affixed my signature in presence of two witnesses.

GEORGE W. FITZ.
